UNITED STATES PATENT OFFICE.

CHARLES H. MOHLAND, OF BURLINGTON, IOWA.

ROPE-CLAMP.

SPECIFICATION forming part of Letters Patent No. 738,562, dated September 8, 1903.

Application filed February 11, 1902. Serial No. 93,592. (No model.)

To all whom it may concern:

Be it known that I, CHARLES H. MOHLAND, a citizen of the United States, and a resident of Burlington, in the county of Des Moines and State of Iowa, have made a certain new and useful Invention in Wire-Rope Clamps; and I declare the following to be a full, clear, and exact description of the same, such as will enable others skilled in the art to which it applies to make and use the invention, reference being had to the accompanying drawings, and to letters of reference marked thereon, which form a part of this specification.

Figure 1 is a side elevation of my invention as applied. Fig. 2 is a section on the line 2 2, Fig. 1. Fig. 3 is a plan view of one of the sections A.

This invention has relation to clamps for the ends of wire ropes, and has for its object the provision of a simple and efficient clamp of this nature which will bite or grip both sides of each section of the rope passing therethrough, the line of compression being retained in the plane of the doubled rope.

With this object in view the invention consists in the novel construction and combination of parts, as hereinafter described, and pointed out in the appended claims.

Referring to the accompanying drawings, the letters A A designate the outer sections or jaws of my clamp, and B the middle section or jaw, located between such outer sections, these jaws having lateral perforated extensions a b for the passage of the connecting-bolts b' and being separated by intervals for purpose of adjustment. C is the rope, doubled at its end and passing through the clamp between the sections thereof, the middle sec-

tion being located between the doubled portions of the rope and biting or gripping adjacent or inner sides of such portions and the outer clamp-sections gripping the outer sides of such portions. The faces of the clamp-jaws are grooved to receive the rope, and the walls of such grooves have oblique corrugations d, having the same inclination as that of the strands of the rope. The sections or jaws are of flat character, and the intermediate jaw has bolt-perforations therethrough which are of larger diameter than that of the bolts, so as to allow such jaw to tip to one side or the other, as may be required in case of inequalities in the rope or in the adjustment of the connecting-bolts.

Having thus described my invention, what I claim as new, and desire to secure by Letters Patent, is—

1. In a rope-clamp, the two outer sections or jaws, and the intermediate automatically-adjustable section, each section having bolt-perforations, and connecting-bolts engaging said perforations, substantially as specified.

2. In a rope-clamp, the two outer sections or jaws, and the intermediate automatically-adjustable section or jaw, each jaw having bolt-perforations, and the connecting-bolts, the perforations of said intermediate jaw being of larger diameter than that of the bolts, substantially as specified.

In testimony whereof I affix my signature in presence of two witnesses.

C. H. MOHLAND.
